UNITED STATES PATENT OFFICE.

THOMAS F. LYNCH, OF LYNN, MASSACHUSETTS, ASSIGNOR TO NATIONAL ADHESIVE COMPANY, INC., OF LYNN, MASSACHUSETTS, A CORPORATION OF MASSACHUSETTS.

PASTING-MACHINE.

1,211,951.

Specification of Letters Patent.

Patented Jan. 9, 1917.

Application filed March 21, 1916. Serial No. 85,716.

To all whom it may concern:

Be it known that I, THOMAS F. LYNCH, a citizen of the United States, residing at Lynn, county of Essex, State of Massachusetts, have invented an Improvement in Pasting-Machines, of which the following description, in connection with the accompanying drawing, is a specification, like characters on the drawing representing like parts.

This invention relates to machines which are adapted to apply cement, paste, glue or similar adhesive substances to sheet material.

More particularly does this invention relate to machines designed to apply an adhesive to cloth or similar materials used in the manufacture of shoes. In this art it has been found desirable to apply the adhesive to shoes in a plurality of relatively small areas instead of coating the whole sheet. This has generally been accomplished by means of meshed adhesive beds upon which the sheet is forcibly pressed, or by fingered instrumentalities which deposit small circles or squares of the adhesive upon a positioned sheet or other object. This novel machine applies the adhesive in lines on the face of the sheet. Herein, the adhesive is applied preferably by means of a grating, a reticular member or a grid which is submersible in the adhesive reservoir and is reciprocally mounted so that it can be raised into emerged position and there retained. As the grid is raised from the reservoir, small amounts of adhesive rest upon the upper surface of the novel grid parts and, upon the positioning of the article to be coated thereupon, the adhesive is transferred to the article in a plurality of stripes or lines.

The object of this invention is to provide a novel machine to apply adhesive to objects which is simple, rapid and efficient in operation.

A more specific object is to provide a machine, the adhesive applying portion of which is easily demountable for replacements or repairs.

Another object is to provide such a machine with a novel grid and grid-operating means.

Other objects of the invention will more fully appear from the following description and the accompanying drawings and will be pointed out in the annexed claims.

In the accompanying drawings, there has been disclosed a machine which is designed to carry out the invention; but which is not to be confined to the exact features there shown, as it is understood that many changes and alterations may be made while still keeping reasonably within the spirit of this invention.

In the drawings, Figure 1 is a side elevation of the machine mounted on a table or bench; Fig. 2 is a plan view of the machine; Fig. 3 is an enlarged sectional detail of the grid showing how the wires are supported and carried.

The novel device is adapted to be mounted upon a suitable support such as a bench or top 1, the legs thereof, which rest upon the floor 2, are not necessary to be shown. The adhesive reservoir 3 is superposed on the table top 1 and is of any suitable material, size or shape, being here shown as generally rectangular in shape. This reservoir 3 is constructed preferably in the form of a relatively shallow receptacle and is filled with an adhesive fluid which is usually in a more or less viscous state. The desirable level of the adhesive is indicated by the dotted line 4 in Fig. 1. A perforated, reticulated or similar member is provided directly to apply the adhesive to the material to be treated, and for this purpose it has been found preferable to provide a grid 5. This grid is mounted so that it may be held in either submerged or emerged position. And, while the grid may be formed in any suitable manner as by integrally casting the cross members with the frame, or by the use of relatively narrow strips arranged in parallelism or crossed to form a reticulated member, it is preferable to form the cross-bars of a plurality of relatively small diameter strips or wires 6. The frame 7 of the grid is substantially rectangular in shape, corresponding to the shape of the reservoir, although the shape of these parts is not material to the invention. In this embodiment the grid wires 6 have each of their ends received within apertures 8, provided on the inside faces of the sides of the grid frame adjacent to the top. These holes may be easily and accurately drilled in the frame sides. Herein, the grid frame is formed of a metallic substance, usually cast iron. While not essential, it is desirable to provide a transverse spacing member for 110

the wires, such as the bar 9 (best shown in the enlarged detail view, Fig. 3). The wire-holding sides of the frame and the bar 9 are preferably of greater height than the frame ends. The top face of this bar 9 has a plurality of recesses 10, one for each of the wires 6. These recesses or grooves are of such depth that substantially one-half of the circumference of each of the wires 6 is received 5 therein. Such provision is made in order that the grid wires may be suitably retained in alinement in such manner that the material may flatly lie upon the grid. The ends of this bar 9 are preferably provided with 10 T-heads of width of the frame ends and are retained in the ends of the grid frame 7 by means of the screws 12.

In the disclosure shown in the accompanying drawings, a lever system is provided in 20 order that the grid may easily be raised from a position submersed in the adhesive. This system is preferably operable by means of a pedal adjacent the floor. Provision is also made for adjustment of the lever system 25 so that greater or less force or travel of the grid movement may be obtained. In this embodiment, the grid frame 7 is provided with a pair of opposed ears 13 which upwardly project from the grid frame sides. 30 While any suitable means may be employed to raise the grid, a pair of trunnions 14 is provided, one each being borne by an opposed ear 13. The inner end of each of the two trunnions 14 is inserted in an aperture 35 15 of each ear 13 and retained therein by means of the nuts 16. The outer end of each of the two trunnions is received and retained within an aperture in each block 17, terminally carried by the guiding rods 18. 40 These rods 18 are reciprocally mounted in a bearing 19 secured to the support as by screws 20. These trunnions are engaged by the arms 21 of the lifting carriage of the lever system. The opposed grid ends of the 45 arms 21 are preferably notched, as shown in dotted lines in Fig. 1. This construction affords a simple means for engaging the trunnions 14 in such manner that the grid may easily and expeditiously be 50 dismounted for cleansing, repair, replacement, or other purposes. The trunnion-engaging arms 21 are pivotally mounted on the table 1 by means of a pair of brackets 22 supported thereupon and secured thereto by 55 the screws 23. The opposite ends of the lever arms 21 are joined by a transverse bar 24 which in turn has pivotally secured thereto the upper end of the lifting rod 25. Reciprocatory movement is imparted to this 60 rod by means of the lever member 26 which is pivotally mounted in the bracket 27 secured to the underside of the table. This member 26 is similarly pivotally secured both to the rod 25, and, at its opposite end, 65 to one of the adjustment rods 28, the other

adjustment rod 29 is pivotally secured to one end of a pedal lever 30. This lever is pivotally mounted in the bracket 31 positioned upon the floor and is provided with a pedal 32. Vertical adjustment of the effective lengths of the rods 28 and 29 is attained by means of the clamp coupling member 33; while, provision is also made for the variation of the application of the reciprocatory movement of the rod 28 to the transverse lever member 26. The latter is accomplished very simply by the provision of a plurality of apertures 34, each of which is adapted to receive the pivot pin of the block 35 carried by the upper end of the rod 28.

In operation this mechanism is simple, rapid and easy to function. The reservoir is first filled with the adhesive substance desired to be employed. The level of the adhesive is preferably slightly above the level of the wires 6 of the grid when in its lowest position so that it thus covers the tops of the wires. When the pedal 32 is depressed, the lever 26 is rocked about its bracketed pivot which in turn entails the corresponding movement of the arms 21 of the lifting carriage. The trunnion ends of these arms effect the raising of the grid, guided by its rods 18 in the bearing 19. The grid in emerged position, as shown in dotted lines in Fig. 1, has its wires clear of the liquid in the reservoir and presented for the facile emplacement of a piece of sheet material thereupon. As portions of the adhesive are left upon the upper faces of each of the grid wires, the simple positioning of a sheet object upon the grid causes the adhesive to be transferred to the object in a plurality of lines corresponding to the lines of the grid wires. After the object is thus treated, it may be removed and the pedal released whence the grid returns to submerged position. The grid is very easily removed by simply upwardly lifting the grid so that the rods 18 are free from their bearings, the adjustability of the leverage is adequate in range and effective in function while the working parts are few, positive in their action and of relatively low production and maintenance costs.

It is to be understood that the construction disclosed herein is illustrative but not restrictive and that the same may be modified within the meaning and scope of the claims which follow.

Having fully described my invention, what I claim as new and desire to secure by Letters Patent is:

1. In a machine for applying an adhesive, a support therefor; a reservoir for the adhesive; an instrumentality adapted to bear an adhesive comprising a frame, a plurality of members arranged in spaced relation, said members having their respective ends

secured to the frame, means extending transversely of the frame and secured thereto means on said transverse means to engage said members to reinforce and to retain them in said spaced relation; and means for reciprocating said instrumentality into and out of submersed position in the adhesive.

2. In a machine for applying an adhesive, a support therefor; a reservoir for the adhesive; a grid comprising a frame, a plurality of grid-forming members arranged in substantial parallelism and having their respective ends secured to the frame sides, an instrumentality arranged transversely of the grid-forming members, means on said instrumentality to engage each of said grid forming members whereby said members are reinforced and retained in spaced relation; and means for reciprocating the grid into and out of submersed position in the adhesive.

3. In a machine for applying an adhesive, a support therefor; a reservoir for the adhesive; a grid comprising a frame, a plurality of grid-forming members arranged in substantial parallelism and having their respective ends secured to the frame sides, a bar arranged transversely of the grid-forming members and secured to the frame, a

plurality of instrumentalities on said bar 30 each engaging a grid-forming member to reinforce and retain the same in proper spaced relation, said instrumentalities engaging each member whereby the upper portion thereof is free to effect its adhesive-bearing function; and means for reciprocating the grid into and out of submersed position in the adhesive.

4. In a machine for applying an adhesive, a support therefor; a reservoir for the adhesive; a grid comprising a frame, wires arranged in substantial parallelism and having their respective ends secured to the frame sides and a bar extending transversely of the wires and secured to the frame, said bar having a plurality of recesses on its upper face to engage a portion of all the wires whereby the upper portion of each wire is free to effect its adhesive-bearing function and whereby the wires are reinforced and retained in proper spaced relation; and means for reciprocating the wired grid into and out of submersed position in the adhesive.

In testimony whereof, I have signed my 55 name to this specification.

THOMAS F. LYNCH.
